US00D878983S

(12) **United States Design Patent** (10) **Patent No.:** **US D878,983 S**
(45) **Date of Patent:** **** Mar. 24, 2020**

(54) **SHIFTER**

(71) Applicant: **Aircraft Gear Corporation**, Loves Park, IL (US)

(72) Inventor: **Sean M. Carlini**, Rockford, IL (US)

(73) Assignee: **Aircraft Gear Corporation**, Loves Park, IL (US)

(**) Term: **15 Years**

(21) Appl. No.: **29/691,684**

(22) Filed: **May 17, 2019**

Related U.S. Application Data

(62) Division of application No. 29/614,942, filed on Aug. 24, 2017, now Pat. No. Des. 851,565.
